WINDOW CUTTING MEANS FOR ENVELOPE MACHINES

Louis Hoffman, Brooklyn, and August Dalmen, Jamaica, N. Y., assignors to P. L. Andrews Corporation, Brooklyn, N. Y., a corporation of New York

Application February 20, 1945, Serial No. 578,874

4 Claims. (Cl. 164—23)

1

This invention relates to improvements in rotary mechanism for cutting windows in envelope blanks, said mechanism being adapted to be incorporated in an automatic envelope manufacturing machine intermediate the mechanism for gumming and drying the envelope closure flaps and the mechanism for folding and sealing the envelope body flaps by which conversion of a blank into a completed envelope is accomplished.

This invention has for an object to provide a novel window cutting mechanism for an envelope manufacturing machine which comprises a cutting roll means and cooperating bed roll means, said bed roll means having novel blank nipping means to so cooperate with the cutting roll means that a blank engaged therebetween is advanced between said rolls subject to the window cutting operation of the rolls, while nevertheless being firmly held against shifting displacement during the window cutting operation, and especially against displacement or shift under the drag of the cutting die, which is carried by the cutting roll means, as said die initially engages an advanced envelope blank and begins window cutting operation thereupon.

This invention has for another object to provide an arrangement of cooperating window cutting and bed rolls, whereby the cutting roll is disposed to oppose the exterior face of an envelope blank operated upon thereby, so as to cut inwardly through said blank, and consequently so that any bur formed along the cut window bounding edge will be located on the interior face of the envelope blank, and thus interiorly of the finished envelope. To this end, the cutting roll is disposed beneath the bed roll, and said bed roll is provided with picker means to engage and carrying upwardly and away the cutout portions or chips severed from the blank by the window cutting operation; and the invention has for a further object to provide, in cooperative relation to said bed roll, a pneumatic discharge conduit, and means operative to remove chips from the bed roll picker means at a point adjacent to the receiving mouth of said pneumatic discharge conduit, so that the freed chips are subjected to the suction draft of the latter, whereby to be received therein and then conveyed away therethrough.

Other objects of this invention, not at this time more particularly enumerated will be understood from the following detailed description of the same.

An illustrative embodiment of this invention is shown in the accompanying drawings, in which:

Fig. 1 is a transverse vertical sectional view

2

through an envelope manufacturing machine at a point where the window cutting mechanism is located, the cutting and bed rolls of the latter mechanism being shown in elevation; Fig. 2 is a vertical sectional view taken on line 2—2 in Fig. 1, but drawn on an enlarged scale; and Fig. 3 is a transverse vertical sectional view through the cutting and bed rolls, taken on line 3—3 in Fig. 2.

Similar characters of reference are employed in the above described views, to indicate corresponding parts.

Referring to the drawings, the reference character 10 indicates the opposite side frames of an envelope manufacturing machine. Journaled in bearings 11, with which the side frames 10 are provided, is a transverse shaft 12. Located beneath and parallel to the shaft 12 is a shaft 13. Said shaft 13 is journaled in bushings or bearings 14 which are mounted on bracket members 15. Said bracket members 15 are affixed to the side frame 10, and together therewith form a part of the framework of the envelope manufacturing machine. Fixed on said shaft 12 is a driving gear 16 to which operating power, by which the envelope manufacturing machine is actuated, may be applied by suitably arranged transmission means (not shown). The shaft 12 drives the shaft 13 by means of intermeshing gearing comprising the gears 17 and 18.

30 Fixed on the lower shaft 13 is a cutting roll 19. A portion of the cutting roll 19 is cut away to provide a flat seat 20, and mounted on said seat is a radially projecting cutting die means which is suitably shaped to cut a window opening of desired dimensions and peripheral shape in the envelope blank B. In a preferred form thereof as shown, said cutting die means comprises a die block 21 provided on its underside with spaced dowel pins 22. Said dowel pins engaged in sockets

40 which enter the cutting roll body beneath its seat 20, whereby to hold said die block 21 against shifting displacement from its operatively assembled position on the cutting roll. The die block is secured in the described mounted relation to

45 the cutting roll 19 by a countersunk fastening screw 23. Affixed to and surrounding the periphery of the die block 21 is a cutting blade structure 24, the outwardly presented sharpened cutting edges of which project beyond the exterior face of the die block 21, and somewhat beyond the periphery of the cutting roll 19.

50 Fixed on the shaft 12 is a bed roll 27 which is disposed above and in aligned opposition to the cutting roll 19 and its cutting blade structure 24, whereby to support an envelope blank B subject

to the cutting action of the latter. Said bed roll 27 is provided across its circumferential face with a countersunk hardened steel block 28 adapted to oppose and cooperate with the cutting edges of the cutting blade structure 24 during the window cutting operation of the latter. Said block is securely affixed to the bed roll 27 by a countersunk screw 29.

Extending respectively from opposite ends of the bed roll 27 are hub extensions 30 of substantially reduced diameter. Said hub extensions 30 are preferably provided with flanges 31 which are affixed to and which abut the bed roll ends, so that said flanges provide bed roll end faces 32. Fixed on said hub extensions 30 are collars 33 adapted to be disposed in spaced opposition to the bed roll end faces 32. Preferably said hub extensions 30 are provided with external screw threads 34, and said collars 33 are internally threaded to screw onto the threaded hub extensions. Said collars 33 are each provided with a plurality of circumferentially spaced sockets 35 opening out from the inner faces thereof. Mounted contiguous to the inner faces of said collars are annular thrust plates 36. Said thrust plates are provided with rearwardly projecting carrier pins 37 corresponding in position and number to the position and number of sockets in the respectively adjacent collars; said pins being entered in said sockets. Mounted around the carrier pins 37 and housed in the collar sockets 35 are compression springs 38. These compression springs are purchased for thrust upon the bottoms of said collar sockets, and exert strong tensional forward thrust upon the thrust plates 36. Mounted between the thrust plates 36 and the respective bed roll end faces 32 opposed thereby are annular blank nipping plates 39. Said blank nipping plates exceed in diameter the diameter of the bed roll 27. Said blank nipping plates 39 are gripped between the thrust plates 36 and the bed roll end faces 32, so as to be radially yieldable, and yet so frictionally clutched to the bed roll end faces 32 as to rotate therewith. The external peripheries of said blank nipping plates 39 are cooperatively opposed to the cutting roll 19 in straddling relation to the cutting die means carried by the latter, and, when engaged by the periphery of said cutting roll, are shifted radially to an eccentric relation to the axis of rotation of the bed roll 27. It will thus be understood that the blank nipping plates 39 are subject to radially floating and yet clutched relation to the bed roll 27, whereby positive feeding of an envelope blank B through and between the cutting and bed rolls is assured, without risk of shifting displacement of the blank under drag of the window cutting die, as will be hereinafter more particularly explained.

Means is provided for bracing the bed roll 27 and its shaft 12 against reaction or yielding play relative to the cutting roll 19, and, similarly, means is also provided for bracing the cutting roll 19 and its shaft 13 against similar reaction or yielding play relative to the bed roll, whereby the cutting and bed rolls are firmly held in their cooperative working relation so as to assure proper meeting of the cutting die means and bed block, and consequently a clean incising penetration of the cutting edges of the cutting blade structure 24 through a blank B engaged by and passed between said cutting and bed rolls. To this end a transverse tension or brace bar 40 is supported by and between attachment brackets 41 which are affixed to the bearings 44 that support the bed roll shaft 12, thereby disposing said tension or brace bar

to extend from side to side of the machine framework, above and parallel to said bed roll shaft 12. Carried by adjustable jack screws 42, which are threaded downwardly through said tension or brace bar 40, are thrust bearing blocks 43 which thrust downwardly upon the bed roll shaft 12, respectively adjacent to each end of the bed roll assembly. Said jack screws 42 are provided with lock-nuts 42' for securing the same in adjusted relation to the tension or brace bar 40. Similarly, a transverse tension or brace bar 44 is supported by and between attachment brackets 45 which are affixed to the machine side frames 10. This tension or brace bar 44 is disposed to extend, from side to side of the machine framework, below and parallel to the cutting roll shaft 13 and its supports. Threaded upwardly through said tension or brace bar 44 are jack screws 46, the free ends of which thrust upwardly against the framework bracket members 15 by which the cutting roll shaft 13 is supported. Said jack screws 46 are also provided with lock-nuts 47 for securing the same in adjusted relation to the tension or brace bar 44.

25 The bed roll 27 is provided with means for engaging and carrying away from a blank B the portion thereof which is cut away therefrom by the cutting die means, whereby to form the desired window opening in the envelope body. This means comprises a pair of picker pins 48 which project radially from the bed block 28. Said picker pins 48 are mounted in screw-threaded holder elements 49, which are adapted to be screwed into internally threaded sockets provided in the bed block for their reception. The die block 21 of the cutting roll 19 is provided with a pair of yieldable cushion elements 50 to oppose said picker pins 48, whereby to support the portion cut away from the blank B so that it will be pierced and impaled upon the picker pins 48, and thereby carried away from the blank body by the ascending movement of the bed roll 27. Preferably said cushion elements 50 comprise plugs of soft rubber or equivalent yieldable material, which are affixed in sockets provided in the die block 21 for their reception. Said plugs are sized to project from the surface of the die block 21, so that their outer ends lie substantially in the plane of the cutting edges of the cutting blade structure 24.

50 Means is provided for removing impaled cutout portions or chips from the picker pins 48, the same comprising a doctor blade 51, the free edge of which bears tangentially against the upwardly moving surface of the rotated bed roll 27. Said doctor blade 51 may be supported in any suitable way so as to operatively engage the bed roll surface; and to this end may be conveniently mounted on the tension or brace bar 40 to depend therefrom. The free or bed roll engaging edge of said doctor blade 51 is provided with indented notches 52 to provide clearance for the picker pins 48, when the latter are carried past the doctor blade. Affixed to the outer face of the doctor blade are chip lifter fingers 53, the same being secured at their lower ends to the doctor blade body adjacent to the free or bed roll engaging edge of the latter. Said chip lifter fingers 53 incline upwardly and away from the face of the doctor blade 51, so that, as a chip carried upwardly by the picker pins 48 is dislodged from the latter by the doctor blade, said chip will ride upwardly onto said lifter fingers so as to be quickly offset from the face of the doctor blade, and thus quickly and surely brought under the influence 55 of suction of the hereinafter described pneumatic

discharge means by which the chips are received and carried away from the machine. Said pneumatic discharge means comprises an air suction conduit 54, having its open mouth disposed above and so as to closely overhang the doctor blade 51 and its lifter fingers 53; and to this end the receiving end of said conduit 54 may be attached to the tension or brace bar 40 by a suitable bracket connection 55. Any suitable means (not shown) may be provided for inducing a suction flow of air to enter the conduit mouth and to thence move inward therethrough. As the chips are freed from the picker pins 48, and then offset from the doctor blade by the lifter fingers 53, the draft of ingoing air passing into the mouth of the conduit 54 will exercise a strong suction effect upon the freed chips, whereby to catch up the same and thereupon cause them to enter and pass through the conduit 54 to a suitable place of disposal externally of the envelope manufacturing machine.

As is well known to the art a suitable conveyer means (not shown) receives the blanks B discharged from the envelope closure flap gumming and drying mechanism of the envelope manufacturing machine, and after spacing them apart in succession, delivers the same one by one to and for passage through the cutting and bed roll assembly of the window cutting means.

As a blank B is moved toward the cutting and bed roll assembly of this invention, its forward end will be engaged by the periphery of the cutting roll 19 so as to be gripped between the same and the peripheries of the blank nipping plates 39. Since, however, said blank nipping plates 39, by reason of their radial floating relation to the axis of rotation of the bed roll 27, are eccentrically offset relative to said axis of rotation, the periphery of the cutting roll 19 as it advances, will push back the blank nipping plates 39 radially against the resistance of the frictionally clutched engagement of the latter with the bed roll ends. By reason of the resistance of this radial displacement of the nipping plates 39, the latter are caused to effect an extraordinarily strong gripping of the blank B between the same and the cutting roll 19 and consequently the blank is so strongly held in the nip of these parts, as it is advanced thereby, that all tendency to slippage or shifting displacement is overcome, especially at the moment when, during the advance of the blank B, the cutting blade structure 24 of the cutting roll initiates its incising effect upon the body of the blank. By reason of this novel means for control of the blank B as it advances through the cutting and bed roll assembly, precise positioning of the cutout window in desired predetermined location in the blank body is assured.

As is also well known to the art, a suitable conveyer means (not shown) receives the blanks as they issue from the window cutting mechanism, and carries them on to and for operative passage through the body flap folding and sealing mechanism of the envelope manufacturing machine.

Having now described our invention, we claim.

1. Rotary window cutting mechanism for envelope manufacturing machines comprising a cutting roll having radially projecting window cutting die means, a bed roll above and opposed to said cutting roll for cooperation with the cutting die means thereof, one of said rolls having radially floating annular blank nipping plates of enlarged diameter frictionally clutched respectively to opposite end faces thereof so as to rotate

therewith in opposition to the periphery of the other roll, whereby to engage laterally spaced portions of a blank to advance said blank between said rolls, said bed roll having picker means to engage the window cut out portions and carry them away from the blanks, a doctor blade mounted to engage its free edge with an ascending surface of said bed roll whereby to strip said cut out portions from said picker means, an air suction conduit having its receiving mouth positioned adjacently above said doctor blade to receive stripped cut out portions and convey them away, and said doctor blade having on its face lifter fingers inclining away therefrom and upwardly toward said conduit mouth, whereby both faces of a stripped cut portion are exposed to air suction currents.

2. Rotary window cutting mechanism for envelope manufacturing machines comprising a cutting roll having radially projecting window cutting die means, a bed roll opposed to said cutting roll for cooperation with the cutting die means thereof, one of said rolls having hub extensions projecting from its ends, collars adjustably mounted on said respective hub extensions, annular thrust plates adjacent the inner faces of said respective collars, radially floating annular blank nipping plates of enlarged diameter intermediate said respective thrust plates and the adjacent end faces of said latter roll, compression spring means intermediate said collars and thrust plates whereby the latter are caused to axially move said nipping plates respectively into frictionally clutched relation to the adjacent end faces of said latter roll so as to rotate therewith, said nipping plates being opposed to the periphery of the other roll, whereby to engage laterally spaced portions of a blank to advance said blank between said rolls.

3. Rotary window cutting mechanism for envelope manufacturing machines comprising a cutting roll having radially projecting window cutting die means, a bed roll above and opposed to said cutting roll for cooperation with the cutting die means thereof, means to rotate said rolls in cooperative relation, said bed roll having a pair of diametrically enlarged radially floating annular blank nipping plates, means to frictionally clutch said nipping plates respectively to adjacent end faces of said bed roll so as to rotate therewith in opposition to the periphery of said bed roll, said bed roll having picker means to engage the window cut out portions and carry them away from the blanks, a doctor blade mounted to engage its free edge with an ascending surface of said bed roll whereby to strip said cut out portions from said picker means, an air suction conduit having its receiving mouth positioned adjacently above said doctor blade to receive stripped cut out portions and convey them away, and said doctor blade having on its face lifter fingers inclining away therefrom and upwardly toward said conduit mouth, whereby both faces of a stripped cut out portion are exposed to air suction currents.

4. Rotary window cutting mechanism for envelope manufacturing machines comprising a cutting roll having radially projecting window cutting die means, a bed roll above and opposed to said cutting roll for cooperation with the cutting die means thereof, means to rotate said rolls in cooperative relation, said bed roll having hub extensions projecting from its ends, collars adjustably mounted on said respective hub extensions, annular thrust plates adjacent the inner faces of

said respective collars, diametrically enlarged radially floating annular blank nipping plates intermediate said respective thrust plates and the adjacent end faces of said bed roll, compression spring means intermediate said collars and thrust plates whereby the latter are caused to axially move said nipping plates respectively into frictionally clutched relation to the adjacent end faces of said bed roll so as to rotate therewith, said nipping plates being opposed to said cutting roll for cooperation with the periphery thereof, said bed roll having picker means to engage the window cut out portions and carry them away from the blanks, a doctor blade mounted to engage its free edge with an ascending surface of said bed roll whereby to strip said cut out portions from said picker means, an air suction conduit having its receiving mouth positioned adjacently above said doctor blade to receive stripped cut out portions and convey them away,

and said doctor blade having on its face litter fingers inclining away therefrom and upwardly toward said conduit mouth, whereby both faces of a stripped cut out portion are exposed to air suction currents.

LOUIS HOFFMAN,
AUGUST DALMEN.
